DESIGN FOR A CHEST FOR STORING AND
DISPLAYING SURGICAL INSTRUMENTS

André Haller, Zurich, Switzerland

Application February 4, 1947, Serial No. 136,671
In Switzerland January 18, 1944

Section 1, Public Law 690, August 8, 1946

Term of patent 14 years

(Cl. D33—19)

To all whom it may concern:

Be it known that I, André Haller, a citizen of the Swiss Republic, and a resident of Waldegg Uitikon, Canton of Zurich, Switzerland, have invented a new, original, and ornamental Design for Chest for Storing and Displaying Surgical Instruments, of which the following is a specification, reference being had to the accompanying drawing, forming a part thereof.

Figure 1 is a perspective view of the chest having a portion forming part of a cylinder to which a prismatic portion joins, according to my new design;

Figure 2 is a top view.

I claim:

The ornamental design for chest for storing

and displaying surgical instruments, substantially as shown.

ANDRÉ HALLER.
